MINE AND TORPEDO GUARD FOR VESSELS.

1,267,909.

Specification of Letters Patent. Patented May 28, 1918.

Application filed August 20, 1917. Serial No. 187,040.

To all whom it may concern:

Be it known that I, JOSEPH E. RUZYCKI, a subject of the Emperor of Austria, residing at Holyoke, in the county of Hampden and 5 State of Massachusetts, United States of America, have invented a new and useful Mine and Torpedo Guard for Vessels, of which the following is a specification.

My invention relates to improvements in 10 guards provided to warn ships or vessels of the presence of submerged mines in their immediate vicinity and to protect such ships or vessels from torpedoes discharged at them by submarines; and said invention resides in 15 a floating frame or cage equipped with propelling and steering means, and adapted to open to receive and surround a vessel or to permit such vessel to leave such cage or the latter to depart from the former, as the case 20 may be; mine-catching means at the front end of said cage, with which means an alarm is associated or connected; a plurality of cartridges and discharging mechanisms therefor carried by said cage, and electric 25 means whereby a torpedo in coming into contact with one or more of certain members of said cage, which are in the path of such torpedo and between the latter and the hull of a vessel within the cage, causes adjacent 30 cartridges to be discharged, with the result that the percussion or primarily-explosive head or nose of such torpedo is cut off or destroyed, the onrush of said torpedo is checked, and the explosion of the torpedo is 35 either aborted altogether or produced at a point sufficiently remote from said hull to avoid seriously damaging the same, all as hereinafter set forth.

The primary object of my invention is to 40 produce a protector or guard for ships or vessels, whereby the same are saved from submerged mines and torpedoes from submarines, such guard being an independent element, that is, an element which does not 45 form part of and is not attached directly to a vessel, but is capable of being employed in connection with any vessel and any number of vessels separately, assuming that none of such vessels exceeds the capacity of said 50 guard.

With this guard in place around a vessel, the presence of a mine in the vessel's course is detected and such mine caught in time to prevent an explosion, the mine being 55 dragged along in the water without explod-

ing, after the alarm has sounded or while it is sounding, and until the guard and the vessel can be stopped, when said mine or its float chain is disconnected from the guard and the mine either hauled on board the 60 vessel or permitted to sink to the bottom of the ocean; and a torpedo discharged at said vessel is destroyed before it reaches the vessel.

This guard, being adapted for or applicable to any number of vessels within a certain maximum size, is economically superior, of course, to a guard or protector that is directly and intimately united with and to a greater or less extent forms a part of the 70 vessel, and is, moreover, superior in point of safety.

Other objects and advantages will appear in the course of the following description.

A preferred embodiment of my invention, 75 whereby I attain the objects and secure the advantages of the same, is illustrated in the accompanying drawings, and I will proceed to describe said invention with reference to said drawings, although it is to be understood that the form, construction, arrangement, etc., of the parts in various aspects are not material and may be modified without departure from the spirit of the invention.

In the drawings, in which like numerals 85 designate like parts throughout the several views, Figure 1 is a top plan of a guard which embodies a practical form of my invention as aforesaid, the cage of the guard being represented in full lines as closed 90 about a vessel, which latter is indicated in outline, and being represented in broken lines as open for the passage out of such vessel or the passage away from the latter of said cage, as the case may be, and as is 95 necessary when a vessel enters the cage or said cage is propelled into position to inclose said vessel; Fig. 2, an enlarged top plan of a portion of the mine catcher and alarm system; Fig. 3, an enlarged detail, partly in 100 elevation and partly in section, of the propelling and steering mechanism for one side of the guard, taken on lines 3—3, looking in the direction of the associated arrow, in Fig. 4; Fig. 4, a cross section through one of the 105 pilot houses on the case, showing in top plan the contents thereof; Fig. 5, a perspective view of a fragmentary portion of the guard, illustrating one way in which the torpedo may be destroyed when it strikes said guard; 110

Fig. 6, a side elevation of said guard; Fig. 7, an enlarged central vertical section through one of the cartridges, showing the firing mechanism in elevation; Fig. 8, a top plan 5 of a fragmentary part of one of the top rails of the cage and of two cartridges supported thereby, showing the manner in which said cartridges are supported; Fig. 9, an enlarged cross section, on lines 9—9, looking in 10 the direction of the associated arrow, Fig. 10, and, Fig. 10, an enlarged side elevation of a portion of one side of the cage, with portions broken away.

Inasmuch as this guard is a thing quite 15 apart from any vessel which it is designed to protect, it is necessary that said guard be self-sustaining in the water, and be equipped with its own propelling and steering mechanisms, and also that it furnish 20 whatever electricity may be required for the operation of the mine alarm and for firing the cartridges, in short, that the guard be quite independent structurally and functionally, including equipment, of any vessel. 25 Generally speaking, therefore, the guard consists of a floating cage having gates to open and close, and provided with a mine catcher situated well forward of said cage on a pair of forwardly-extending rods 1, 30 propellers 2—2, one for each gate, driving mechanism and steering apparatus, means to supply the required electricity for the several circuits, and the torpedo-destroying elements. A pilot house 4 may be mounted 35 at the stern of the aforesaid cage on each side or on each of the aforesaid gates near their stern ends.

In the first view a vessel 5 is represented in outline in the cage, and guy-lines are 40 represented at 6 as extending between said vessel and said cage. When the cage is open, as indicated by broken lines, the cage can be propelled forward away from the vessel 5, or the latter backed out of said cage, on 45 the one hand; and said cage can be propelled backward into inclosing relation to the vessel, or the latter driven forward into said cage, on the other hand.

The cage, or more correctly perhaps the 50 frame of the cage, comprises V-shaped, top and bottom bars or rails 7 and 8, respectively, two top bars or rails 10 which have their forward ends hinged at 11—11 to the ends of said rails 7, and their rear terminals 55 turned inwardly toward each other and arranged for engagement at 12, when the gates, of which said rails form parts, are closed, two bottom bars or rails 13, each of which has its forward end hinged at 14 to one end 60 of said rail 8, a plurality of uprights 15 connecting the aforesaid top and bottom V-shaped rails, a plurality of uprights 16 connecting said top rails 10 with said bottom rails 13, the latter having little or no projection at their rear end, beyond the rear 65

uprights 16, a V-shaped rail 17 spaced from said rail 8 and connected with said uprights 15, and a rail 18 on each side spaced from said rail 13 on such side and connected with said uprights 16. This frame is supported in the water on a plurality of pairs of floats 19 attached to the ends of a plurality of arms 20 which in turn are attached to the undersides of the rails 7 and 10, such arms extending crosswise of said rails. A 70 covering or casing is represented at 22, in Fig. 6, for the circuit-forming members which supply the electric current to certain cartridges 23 in a series, when certain contacts or connections are made, as by a torpedo, as 24 in Fig. 5, striking or encountering one or more of a series of vertical contact strips 25. The contact strips 25 extend between the bars 7 and 10 at the top and the bars 17 and 18 at the bottom. The middle 75 portions of the strips 25 are broken out in Figs. 9 and 10 in order to economize space.

The V-shaped members and their connecting uprights form the prow and the members hinged thereto constitute the gates of 80 the cage.

The cage is supported by the floats 19 quite 85 low in the water, so that the contact strips 25 are in the path of any torpedo that may be fired at the vessel 5 and which would 90 strike the same in the absence of protecting means, and the mine catcher is carried in position to do its work effectually.

As the power-generating means I may 95 provide an internal-combustion engine 26 in each pilot house 4, as a source of supply 100 of the required electric energy, which supply is of comparatively low voltage. A generator or dynamo 27 may be provided in either or both of the pilot houses—see Figs. 105 3 and 4. The engine 26 has a shaft 28 upon which are secured two gears 29 and 30, the latter being a bevel-gear. A long, vertical, tubular member or sleeve 31 is journaled in the floor of each house 4, and in a lug 32 110 that projects rearwardly from each of the rails 18 at a point adjacent to the rearmost upright 16 with which such rail is connected. Secured on the sleeve 31, at the upper end above the pilot-house floor, is a 115 bevel-gear 33 which intermeshes with the bevel-gear 30. A bevel-gear 34 is secured on the sleeve 31, under the supporting, bearing lug 32. A vertical, steering post 35 is journaled at the top in a bracket 36 which 120 extends inwardly from the front side of the house 4, passes down into and through the sleeve 31, and has a collar 37 secured on the lower, protruding terminal of said post. One of the propellers 2 is secured on the 125 outer end of a sleeve 38 which is mounted on a rearwardly-extending axle 39 that has its forward end affixed in the collar 37. A bevel-gear 40 is secured on the horizontal sleeve 38, and intermeshes with the bevel- 130

gear 34. Thus it will be seen that the propeller 2 is driven from the engine 26, through the medium of the shaft 28, bevel-gears 30 and 33, sleeve 31, bevel-gears 34 and 40, and 5 sleeve 38. And it will be seen, furthermore, that the axle 39, with the sleeve 38 and propeller 2 thereon, can be turned in either direction and to any required degree on a horizontal plane, for steering purposes, by 10 means of the post 35, and collar 37. The sleeve 31 runs loosely on the post 35, as does the sleeve 38 on the axle 39. In Fig. 3, the middle portions of the steering post 35 and the sleeve 31 are broken out.

15 The steering post 35 is operated for steering purposes by means of a pulley 41 secured to said post beneath the bearing bracket 36, a pulley 42 secured on a horizontal shaft 43, a belt 44 connecting said pulleys, and a 20 steering wheel 45 also secured on said shaft, the latter being journaled in a bearing 46 on the front of the house 4, inside, and a bearing 47 supported from the floor of said house. The post 35 is rotated by the steering 25 wheel 45 in either direction, according to the direction given said wheel, through the medium of the shaft 43, pulley 42, belt 44, and pulley 41.

The propellers 2, with their driving and 30 oscillatory or steering mechanisms, drive and guide the cage in any direction, and also open and close the gates of said cage to provide an entrance or exit for the vessel.

The dynamo 27 has a shaft 48 upon which 35 is secured a gear 49 which intermeshes with the gear 29. Said dynamo is thus driven from the engine 26. There is an electric annunciator or bell in one or each of the houses 4, one such bell being represented at 40 50 in Fig. 4. A circuit from and to the dynamo 27, through the bell 50, includes wires 51 and 52, the latter being grounded on the frame. There is also another circuit from and to the dynamo, which circuit comprises 45 wires 53 and 54. The wires 53 and 54 enter the casing 22 adjacent to one end and pass to the other end thereof. Although the casing 22 does not appear in Fig. 1, the wires 53 and 54 are broken off in that view 50 at the places where they would enter said casing if present, because of the impracticability of making a further showing of said wires in said view. The wire 51 terminates at its forward end at a contact 55 bar 55.

Taking up next the mine catcher and alarm mechanism at the front end of the guard, and having special reference to Figs. 1, 2, and 6, it will be observed that the rods 60 1 are bent upwardly at their front ends, and support thereon a cross-bar 56 which is provided with the catching and circuit-closing members, among which latter is included the contact bar 55. The cross-bar 56 has forwardly-extending, laterally-divergent, end

pieces 57-57, and between these a series of forwardly-projecting lugs 58. Each lug 58 has at its front end a head 59 which is equipped with a pair of movable flukes 60. Each head 59 is recessed or slotted to receive 70 a pair of flukes 60, and a spring 61. The flukes 60 in each pair are pivoted at 62-62 to their head 59, and the spring 61 is arranged and adapted to bear on said flukes in such a manner that the front ends 75 of the flukes normally abut said head, as shown at 63 in Fig. 2, and their rear ends are separated as widely apart as possible. The end flukes 60 in the set or series extend across the spaces between the projections 80 57 and the outermost lugs 58, nearly over to said projections, and the other flukes extend across the spaces between said lugs, nearly touching each other in the centers of such spaces.

The contact bar 55 is attached at the ends to but insulated from the cross-bar 56, as represented at 64-64. A series of horizontal, headed, push pins 65 are arranged in the cross-bar 56 in front of the bar 55. 90 When any pin 65 is forced back against the bar 55, the bell circuit is closed through said bar and the frame. Normally the pins 65 are held out of contact with the bar 55, and said bell circuit is consequently open, by 95 means of springs 66 on said pins between the cross-bar 56 and the members at the rear ends of said pins. The front ends of the two end pins 65 are loosely connected with short arms 67-67, which are pivoted at 100 68-68 to the cross-bar 56, and two of the springs 66 are inserted between said arms and the cross-bar 56, to retain said pins with their heads out of contact with the bar 55 and against said cross-bar. The front 105 ends of the other pins are located in pairs in the spaces between the lugs 58, and such ends are connected by short bars 69, with the springs 66 for such pins between said bars and the cross-bar 56.

It is now plainly to be seen that, as the mine catcher is forced forward through the water, ahead of the cage, any chain which connects a submerged mine with a float, and which is in the path of the cross-bar 56 and its end projections 57, such a chain being represented at 70 in Fig. 2, is encountered by one of or perhaps two of the flukes 60, such fluke or flukes are forced inwardly toward the supporting lugs 58, swinging on 115 their pivots 62 against the resiliency of their springs 61, and said chain is received within the space behind such flukes. Immediately the springs 61 act to close the entrance to the aforesaid space, so that the chain 70 can not get out. The arm 67 or bar 69, as the case may be, in the path of the chain 70, is carried forcibly against said chain, directly the latter is received either 120 between one of the projections 57 and the 130

adjacent lug 58 or between two adjacent lugs 58, with the result that the pin or pins 65 connected with said arm or bar, is or are actuated rearwardly into contact with the insulated bar 55, the bell circuit is closed, and the bell 50 caused to ring. The bell 50 continues to ring until the pressure of the chain 70 on the sliding contact member or members is removed, which it is not liable to be until said chain is released from the confining fluke or flukes. The chain is dragged along by the catcher, until such time as the guard can be stopped, said chain released, and the mine at the end of said chain taken care of in a manner to prevent harm therefrom to the vessel 5.

I will now describe in detail the cartridges 23 and the firing circuits therefor, the latter being connected with the wires 53 and 54 which may be said to form the main, firing circuit and from which the others branch off.

The cartridges 23 are arranged in two rows on opposite sides of the rails 7 and 10. Each cartridge 23 has a vertical flange 71 on one side, which is dovetailed into a corresponding slot 72 in one side or the other of the supporting rail. This dovetailed connection is tapered so as to prevent the cartridge from dropping out of the rail at the bottom—see Fig. 8.

Each cartridge 23 is divided by a horizontal partition 73 into upper and under chambers 74 and 75, respectively, and has a primer or percussion-cap 76 in the center thereof—see Fig. 7. An arm 77 on the partition 73 supports a firing-pin 78 over the percussion-cap 76. A hammer 79, for the firing-pin 78, is pivoted at 80 to a post 81 rising from the partition 73. A spring 82 is arranged between the partition 73 and the hammer 79 to cause said hammer, when set, to strike the firing-pin 78 a sufficiently hard blow to cause the percussion-cap 76 to be exploded by said pin. A trip or latch 83 is pivoted at 84 to a lug 85 on the partition 73, and extends upwardly to engage the tail end of the hammer 79 and retain the head end of said hammer, against the resiliency of the spring 82, in elevated and striking position, until said latch is actuated to release the hammer to said spring, when said hammer is caused to strike the blow that discharges the cartridge. The latch 83 is provided with an armature 86, and an electro-magnet 87 is placed in the chamber 74 in position to attract, when said magnet is energized, said armature and draw said latch out of engagement with the hammer 79. Binding posts for the electro-magnet connections are represented at 88.

As also appears in Fig. 7, there is an explosive substance 89 in the cartridge chamber 75, immediately under the partition 73 and the percussion-cap 76 therein, and a projectile 90 in said chamber under said explo-

sive substance. The projectile 90 may have at its exposed end or base a sharp-edged, arcuate, blade 91 designed especially for penetrating torpedoes.

The contact strips 25, as here represented, are flat with top and bottom rod-like terminals or shanks 92 and 93, respectively. The strips 25 are arranged with their flat sides at right-angles to the longitudinal, vertical planes of the bars which support said strips, because in this way the strips are less liable to be broken by and afford better contact surfaces for torpedoes. Said strips are in vertical planes which alternate with the vertical planes of the cartridges 23.

As clearly shown in Fig. 10, the upper terminal or shank 92 of each strip is received in a flanged, insulator bushing 94 in either rail 10 (or the rail 7), and the lower terminal or shank 93 of such strip is received in a flanged, insulator bushing 95 in either rail 18 (or the rail 17). Each shank 93 is screw-threaded at the bottom to receive a nut 96 which bears against the flanged end of the contiguous bushing 95. Mounted on the top of each shank 92, and separated from the flanged end of the bushing 94 below by an interposed spring 97, is an insulator block 98 which is equipped with two contact pieces 99. The contact strips 25 are thus insulated from their supporting rails, and held up with their nuts 96 against the bottom ends of the insulator bushings 95, by the springs 97, as shown in Figs. 9 and 10. In the event a contact strip 25 is broken, its shank 92, with the part of said strip above the break, is forced upward by the associated spring 97, until the contact pieces 99 on the block 98 on said shank come into contact with two contact pieces 101 and 102 above. The contact pieces 101 and 102 are carried by a bar 103, but insulated from said bar as represented at 104. The bar 103 is supported from the rails 7 and 10, above the series of insulator blocks 98, on posts 105. There is a series of binding-posts 106 arranged in pairs on either rail 10, also on the rail 7.

In practice the parts above the rails 7 and 10 which have been described, and also major portions of the main, firing-circuit wires 53 and 54, and of the branch, firing-circuit wires described below, are contained in the casing 22.

A wire 107 leads from the wire 53 to each contact piece 101, and a wire 108 leads from the wire 54 to each contact piece 102. Wires 109 connect the wire 53 with alternate contact strips 25, and wires 111 connect said wire 53 with the lower binding-posts 88 on alternate cartridges; while wires 110 connect the wire 54 with the intervening strips 25, and wires 112 connect said wire 54 with corresponding binding posts on the intervening cartridges. A wire 100 leads from each end of each contact piece 99 to the adjacent bind-

ing-post 106, and a wire 113 leads from such post to the upper binding-post 88 on the adjacent cartridge 23. A wire 114 leads from the upper binding-post 88 on each cartridge 5 to the adjacent strip 25.

Assuming, now, that the torpedo 24, Fig. 5, thrusts its nose between any two adjacent contact strips 25, the circuits through the two cartridges 23 (inside and outside) 10 which are above said nose, or through the electro-magnets 87 in said cartridges, are closed and said cartridges are fired. The two projectiles 90, thus discharged upon the the nose of the torpedo below, strike the 15 same and render the torpedo harmless, at least so far as the vessel 5 is concerned. The branch circuit closed by the torpedo through two adjacent strips 25, between the wires 53 and 54, comprises either the wire 109 which 20 leads from said wire 53 to one of said strips, or the two wires 111 which lead from said wire 53 to the two cartridges included in said branch circuit and which are fired, the two wires 114 between said cartridges 25 and one of said strips, and either the wires 112 which lead from said cartridges to said wire 54, or the wire 110 that leads from one of said strips to said wire 54, according to which pair of strips 30 said torpedo contacts with.

If the right- and left-hand strips 25, with which the torpedo contacts, are two which are connected with the wires 53 and 54 by two of the wires 109 and 110, respectively, the paths taken by the current in actuating the firing means are through the wire 53, the wires 111 that extend from said wire 53 to the cartridges fired, the wires 114 that extend from said 40 cartridges to said right-hand strip, through the latter, said torpedo, said left-hand strip, and the wires 110 and 54. And if the right- and left-hand strips 25, with which the torpedo contacts, are two which are connected with the wires 54 and 53 by two of the wires 110 and 109, respectively, the paths taken by the current in actuating the firing means are through said wires 53 and 109, said left-hand strip, said torpedo, said 45 right-hand strip, and wires 114 that extend from said right-hand strip to the cartridges fired, the wires 112 that extend from said cartridges to said wire 54, and the latter.

In case one of the strips 25 be broken by 55 the torpedo, the spring 97, which encircles the shank 92 of such strip, immediately acts to thrust the parts including two of the contact pieces 99 upwardly and to force the latter against the contact pieces 101 and 102 above. This closes the branch circuits in 60 which four cartridges 23 are included, such cartridges being the two pairs flanking the broken contact strip, and instantly said cartridges are fired and their projectiles discharged at the torpedo below. Each of two

of said branch circuits, from the wire 53 to the wire 54, includes one of the wires 107, one each of the contact pieces 101 and 99, one of the wires 100, one of the binding-posts 106, one of the wires 113, and one of 70 the wires 112, and each of the other two of said branch circuits, from said wire 53 to said wire 54, includes one each of the wires 111, 113, and 100, one of the contact pieces 99 and the contact piece 102 which 75 the piece 99 is bearing against, and one of the wires 108.

When one of the strips 25 is broken and the contact pieces 99 above the broken strip are thrust against the companion contact pieces 101 and 102, the paths taken by the current in actuating the firing means are respectively from the wire 53 through the wire 107 that extends from said wire 53 to the contact piece 101, through said contact 80 piece 101 and the contiguous contact piece 99, the wires 100 that extend from said contact piece 99 to two of the binding-posts 106, the wires 113 that extend from said binding-posts to two of the four cartridges 90 fired, one in front and one behind, and the wires 112 that extend from said cartridges to the wire 54; and from the wire 53 through the wire 111 that extends from said wire 53 to the other two cartridges fired, 95 one in front and one behind as before, the wires 113 that extend from said cartridges to two other binding-posts 106, the wires 100 that extend from said binding-posts to the contact piece 99 that is contiguous 100 with said contact piece 102, through said contact pieces, and the wire 108 that extends from said contact piece 102 to said wire 54.

The operation of the guard as a whole 105 will be very well understood from the foregoing description, so that little further need be said in regard to the same. When a vessel is to be inclosed, the gates are swung open and either said vessel is run into said 110 guard while the latter is stationary or comparatively so, or said guard is backed under its own power into inclosing position. Then the gates are closed, and the guy-ropes 6 are made fast to the vessel. The latter now continues on its way, either with or without the assistance of the motive power with which the guard is provided. If a mine chain is encountered, it is caught 115 and the alarm given, as previously explained. Or, if a torpedo be fired at the vessel, the same is destroyed or prevented from damaging the vessel, in the manner hereinbefore set forth in detail. In the first instance the bell 50 continues to ring 120 until the pressure of the chain 70 on either one of the arms 67 or one of the bars 69 is removed, so that the displaced pin or pins 75 can be actuated, by the controlling spring or springs 66, out of contact with 125 130

the bar 55. And, in the second instance, only the cartridges 23 in the branch circuits affected are discharged. These discharged cartridges are subsequently replaced.

5. The connections between the cartridges 23 are of a nature to hold said cartridges in place when fired.

When the protection of the guard for the vessel is no longer needed, the guy-ropes 6 10 are thrown off, the gates are opened, and the vessel or guard is maneuvered to separate the one from the other.

The mine catcher and alarm might be omitted, but they are of great advantage 15 and preferably and usually will be retained.

It is obvious that separate bells and circuits for the several mine-catcher units may be provided, if desired, in order to disclose with which of such units a chain is caught.

20. The circuit-forming and other members which are mounted on the rails 7 and 10 and pass over the hinge connections at 11, must be sufficiently loose and flexible or break joints, according to their nature, so as not 25 to interfere with the articulation of the gates, of which said rails 10 constitute parts.

What I claim as my invention, and desire to secure by Letters Patent, is—

30. 1. The combination, in a guard for vessels, with a partially submerged floating skeleton frame capable of inclosing a vessel, and explosive members carried by said frame, of a source of electrical energy, and 35 circuit-forming members to explode said first-named members, when the circuit through said circuit-forming members is closed, as by contact with the latter of a torpedo.

40. 2. The combination, in a guard for vessels, with a partially submerged floating skeleton frame capable of inclosing a vessel, and a series of explosive members carried by said frame, of a source of electrical energy, and circuit-forming members to explode certain of said first-named members in said series, when and accordingly as the circuit through said circuit-forming members is closed.

45. 3. The combination, in a guard for vessels, with a partially submerged floating skeleton frame capable of inclosing a vessel, and a series of explosive members carried by said frame, of a source of electrical energy, and 55 circuit-forming members to explode certain of said first-named members in said series, when and accordingly as the circuit is closed through two of said circuit-forming members.

50. 4. The combination, in a guard for vessels, with a partially submerged floating frame, and a series of explosive members carried by said frame, of a source of electrical energy, and circuit-forming members to

explode certain of said first-named members 65 in said series, when and accordingly as the circuit is closed by the breaking of one of said circuit-forming members.

5. The combination, in a guard for vessels with a partially submerged floating 70 frame, and a series of explosive members carried by said frame, of a source of electrical energy, and circuit-forming members to explode certain of said first-named members in said series, when and accordingly as the 75 circuit is closed through two of said circuit-forming members, and to explode certain of said first-named members in said series, by the breaking of one of said circuit-forming members.

6. The combination, in a guard for vessels, with a partially submerged floating skeleton frame capable of inclosing a vessel, and cartridges carried by said frame, of a series of contact-members attached to but 80 insulated from said frame, a source of electrical energy, and circuit-forming members connecting such source with said contact members and said cartridges, the construction and arrangement of parts being such 85 that the circuit may be closed by contacting connections between any two of said contact members which are adjacent to each other, to explode said cartridge.

7. The combination, in a guard for vessels, with a partially submerged floating frame, and cartridges carried by said frame, of a series of contact members attached to but insulated from said frame, a source of 90 electrical energy, and circuit-forming members connecting such source with said contact members and said cartridges, the construction and arrangement of parts being 95 such that the circuit may be closed by breaking any one of said contact members, to explode said cartridges.

8. The combination, in a guard for vessels, with a partially submerged floating frame, and cartridges carried by said frame, of a series of contact members attached to 100 but insulated from said frame, a source of electrical energy, and circuit-forming members connecting such source with said contact members and said cartridges, the construction and arrangement of parts being 105 such that the circuit may be closed by contacting connection between any two of said contact members which are adjacent to each other, and by breaking any one of said contact members, to explode said cartridges.

9. In a guard for vessels, a partially submerged floating frame, a cartridge carried by said frame, a contact member attached to but insulated from said frame, a spring tending to force said member in one direction, a source of electrical energy, circuit-forming members, and means to close the circuit through said last-named members.

and fire said cartridge, upon the breaking of said contact member and release of part thereof to said spring.

10. In a guard for vessels, a partially submerged floating frame, cartridges carried by said frame, a contact member attached to but insulated from said frame, a spring tending to urge said member in one direction, insulated contact pieces carried by said contact member, a source of electrical energy, and circuit-forming members, the latter consisting in part of insulated contact pieces located in the paths of said first-named contact pieces, when the latter are projected toward the same, upon the breaking of said contact member and release of part thereof to said spring, whereby the circuit is closed and said cartridges are fired.

11. In a guard, for vessels, a partially submerged floating frame, cartridges carried by said frame, and electrical means to fire said cartridges, such means consisting in part of circuit-forming members interposed between a vessel within said frame and any torpedo that may be accurately fired thereat, and capable of closing the firing circuits when contacted with by such torpedo.

12. The combination, in a guard for vessels, with a partially submerged floating frame, contact members attached to but insulated from said frame, and cartridges carried by said frame in alternate relationship to said members, of electrical means to fire the cartridges between the vertical planes of any two adjacent contact members when connected, as by contact therewith of a torpedo.

13. The combination, in a guard for vessels, with a partially submerged floating frame, contact members attached to but insulated from said frame, means to project a part of any of said contact members which may be broken, as by the impact therewith of a torpedo, and cartridges carried by said frame in alternate relationship to said members, of electrical means to fire the cartridges on both sides of the vertical plane of any contact member, in the event such member be broken, such means including circuit-closing members in operative position relative to any projected part of a broken contact member.

14. The combination, in a guard for vessels, with a partially submerged floating frame, contact members attached to but insulated from said frame, means to project a part of any of said contact members which may be broken, as by the impact therewith of a torpedo, and cartridges carried by said frame in alternate relationship to said members, of electrical means to fire the cartridges between the vertical planes of any two adjacent contact members when connected, as by contact therewith of a torpedo, and electrical means to fire the cartridges on both sides of the vertical plane of any contact member, in the event such member be broken, such means including circuit-closing members in operative relation to any projected part of a broken contact member.

JOSEPH E. RUZYCKI.
